Primary Examiner — Susan E Krakower(74) *Attorney, Agent, or Firm* — Dorsey & Whitney LLP(57) **CLAIM**

The ornamental design for an exercise bike flywheel, as shown and described.

DESCRIPTION

FIG. 1 shows a front perspective view of a flywheel for an exercise bike;

FIG. 2 shows a front elevation view of the flywheel of FIG. 1; FIG. 3 shows a left elevation view of the flywheel of FIG. 1; and,

FIG. 4 shows a right elevation view of the flywheel of FIG. 1. The rear elevation view of the flywheel is a mirror image of the front elevation view of the flywheel.

The broken lines illustrate environmental structure and form no part of the claimed design.
